TELEVISION ANTENNA

Mack Kohl, Hampshire, Ill., assignor to Joseph N. Marks, Julius Tunkl, I. Rosenthal, and E. Lichtenstein, doing business as Tricraft Products Co., Chicago, Ill.

Application February 23, 1952, Serial No. 18,642

Term of patent 3½ years

(Cl. D26—14)

To all whom it may concern:

Be it known that I, Mack Kohl, a citizen of the United States, residing at Hampshire, in the county of Kane and State of Illinois, have invented a new, original, and ornamental Design for Television Antenna, of which the following is a specification, reference being had to the accompanying drawing, forming a part thereof, in which:

Fig. 1 is a perspective view of a television antenna embodying my new design;

Fig. 2 is a top plan view of the television antenna shown in Fig. 1 with the mast and sail structure removed; and

Fig. 3 is a fragmentary cross sectional view taken along lines 3—3 in Fig. 2, with the mast and sail structure attached.

I claim:

The ornamental design for a television antenna, substantially as shown.

MACK KOHL.
